(57) **CLAIM**

The ornamental design for a transducer shield, as shown and described.

DESCRIPTION

FIG. 1 is a perspective view of my new transducer shield design taken generally from the front and looking upwards towards the bottom;

FIG. 2 is a front elevation view of the transducer shield depicted in FIG. 1;

FIG. 3 is a left side elevation view of the transducer shield depicted in FIG. 1;

FIG. 4 is a right side elevation view of the transducer shield depicted in FIG. 1;

FIG. 5 is a top plan view of the transducer shield depicted in FIG. 1;

FIG. 6 is a bottom plan view of the transducer shield depicted in FIG. 1;

FIG. 7 is a rear elevation view of the transducer shield depicted in FIG. 1; and,

FIG. 8 is a perspective view of an alternate embodiment of the present design taken generally from the rear and looking downwards toward the top.

The dashed lines showing the environment in FIG. 1 are for illustrative purposes only and form no part of the claimed design.
